CLAIM

The ornamental design for an electronic device, as shown and described.

DESCRIPTION

FIG. 1 is a perspective view of a first embodiment of an electronic device showing our new design;
FIG. 2 is a rear perspective view thereof;
FIG. 3 is another rear perspective view thereof;
FIG. 4 is a front view thereof;
FIG. 5 is a rear view thereof;
FIG. 6 is a left side view thereof;
FIG. 7 is a right side view thereof;
FIG. 8 is a top view thereof;
FIG. 9 is a bottom view thereof;
FIG. 10 is a perspective view of a second embodiment thereof;
FIG. 11 is a rear perspective view thereof;
FIG. 12 is another rear perspective view thereof;
FIG. 13 is a front view thereof;
FIG. 14 is a rear view thereof;
FIG. 15 is a left side view thereof;
FIG. 16 is a right side view thereof;
FIG. 17 is a top view thereof;
FIG. 18 is a bottom view thereof;
FIG. 19 is a perspective view of a third embodiment thereof;
FIG. 20 is a rear perspective view thereof;
FIG. 21 is another rear perspective view thereof;
FIG. 22 is a front view thereof;
FIG. 23 is a rear view thereof;
FIG. 24 is a left side view thereof;
FIG. 25 is a right side view thereof;
FIG. 26 is a top view thereof;
FIG. 27 is a bottom view thereof;
FIG. 28 is a perspective view of a fourth embodiment thereof;
FIG. 29 is a rear perspective view thereof;
FIG. 30 is another rear perspective view thereof;
FIG. 31 is a front view thereof;
FIG. 32 is a rear view thereof;
FIG. 33 is a left side view thereof;
FIG. 34 is a right side view thereof;
FIG. 35 is a top view thereof;
FIG. 36 is a bottom view thereof;
FIG. 37 is a left side view of a fifth embodiment thereof;
FIG. 38 is a right side view thereof;
FIG. 39 is a top view thereof;
FIG. 40 is a bottom view thereof;
FIG. 41 is a left side view of a sixth embodiment thereof;
FIG. 42 is a right side view thereof;
FIG. 43 is a top view thereof;
FIG. 44 is a bottom view thereof;
FIG. 45 is a perspective view of a seventh embodiment thereof;
FIG. 46 is a rear perspective view thereof;

FIG. 47 is another rear perspective view thereof;
FIG. 48 is a front view thereof;
FIG. 49 is a rear view thereof;
FIG. 50 is a left side view thereof;
FIG. 51 is a right side view thereof;
FIG. 52 is a top view thereof;
FIG. 53 is a bottom view thereof;
FIG. 54 is a perspective view of an eighth embodiment thereof;
FIG. 55 is a rear perspective view thereof;
FIG. 56 is another rear perspective view thereof;
FIG. 57 is a front view thereof;
FIG. 58 is a rear view thereof;
FIG. 59 is a left side view thereof;
FIG. 60 is a right side view thereof;
FIG. 61 is a top view thereof;
FIG. 62 is a bottom view thereof;
FIG. 63 is a perspective view of a ninth embodiment thereof;
FIG. 64 is a rear perspective view thereof;
FIG. 65 is another rear perspective view thereof;
FIG. 66 is a front view thereof;
FIG. 67 is a rear view thereof;
FIG. 68 is a left side view thereof;
FIG. 69 is a right side view thereof;
FIG. 70 is a top view thereof;
FIG. 71 is a bottom view thereof;
FIG. 72 is a perspective view of a tenth embodiment thereof;
FIG. 73 is a rear perspective view thereof;
FIG. 74 is another rear perspective view thereof;
FIG. 75 is a front view thereof;
FIG. 76 is a rear view thereof;
FIG. 77 is a left side view thereof;
FIG. 78 is a right side view thereof;
FIG. 79 is a top view thereof;
FIG. 80 is a bottom view thereof;
FIG. 81 is a perspective view of an eleventh embodiment thereof;
FIG. 82 is a rear perspective view thereof;
FIG. 83 is another rear perspective view thereof;
FIG. 84 is a front view thereof;
FIG. 85 is a rear view thereof;
FIG. 86 is a left side view thereof;
FIG. 87 is a right side view thereof;
FIG. 88 is a top view thereof;
FIG. 89 is a bottom view thereof;
FIG. 90 is a perspective view of a twelfth embodiment thereof;
FIG. 91 is a rear perspective view thereof;
FIG. 92 is another rear perspective view thereof;
FIG. 93 is a front view thereof;
FIG. 94 is a rear view thereof;
FIG. 95 is a left side view thereof;
FIG. 96 is a right side view thereof;
FIG. 97 is a top view thereof;
